MASONRY BLOCK CONSTRUCTION

Alfred A. Hala, 28 Meeks Lane, Islip, N.Y. 11751

Filed Dec. 16, 1971, Ser. No. 209,009

Term of patent 14 years

Int. Cl. D25—01

U.S. Cl. D18—2 R

FIG. 1

FIG. 2

FIG. 3

FIG. 4

FIG. 5

FIG. 6

FIG. 1 is a perspective view of a masonry block construction, embodying my new design and pursuant to a first embodiment of the present invention;

FIG. 2 is an end view of the masonry block construction depicted in FIG. 1;

FIG. 3 is a bottom view of the design shown in FIG. 1;

FIG. 4 is a perspective view of a masonry block construction embodying my new design and pursuant to a second embodiment of the present invention;

FIG. 5 is an end view of the masonry block construction depicted in FIG. 4; and

FIG. 6 is a bottom view of the design shown in FIG. 4.

I claim:

The ornamental design for a masonry block construction, substantially as shown and described.
